RAZOR

Edward Siegel, New York, N. Y.

Application October 18, 1932, Serial No. 638,313

8 Claims. (Cl. 30—48)

This invention relates to safety razors; and, more particularly, to safety razors of the so-called hoe type, that is, which are substantially T-shaped in side elevation, with the staff of the 5 T constituting a handle and with the bar of the T constituting a holder for a removable and renewable blade.

As now appraised, the invention is of greatest value in connection with a hoe-type razor of the 10 familiar kind wherein the holder includes two parts, to wit, an underlying member or blade table and an upper member or blade cap, so shaped and arranged that when the removable and renewable blade is double-edged with cutting 15 edges at its opposite sides and is highly flexible and of the thin or so-called ribbon type such a blade can be interposed between the table and the cap and these parts can then be secured together to clamp the blade to set both its edges 20 for shaving while flexing the blade transversely.

The importance of the present invention resides in this, that something long and fruitlessly heretofore sought in the art has been attained, to wit, a true slicing or wiping-shear of the hairs 25 of the beard incidental to easy and natural movement of the blade holder. By a true-slicing or wiping-shear is meant a single sweep of the blade edge over the face being shaved, in such manner that the direction of sweep is the result- 30 ant of two simultaneously performed movements of the blade-edge, one laterally thereof and the other longitudinally thereof, and not only therefore diagonal or oblique to the blade-edge—but also diagonal or oblique to the direction of sweep 35 of the blade itself across the face.

The patents of the prior art are numerous wherein attempts to obtain a true slicing of the blade edge of a hoe-type razor by natural manipulation of the handle thereof are evidently in 40 mind; but, so far as I am aware, none of these proposed structures, when thus manipulated, acts to give a shaving action different from the typical cutting action of the ordinary hoe-type razor as first introduced. Said typical cutting 45 action is a mere pulling of the blade-edge across the hairs to be cut, with such edge actually performing no slicing at all. The result is that the effect produced is a chop or scrape, with the accompanying disadvantages of more or less 50 painful chafing, an uneven and unclean shave, and an appreciable dulling of the blade-edge at the conclusion of, if not during, the first shaving performed with a new blade. Various previous workers in the art, attempting to provide for a 55 natural true-slicing cut of the razor blade edge,

have felt, but quite erroneously, that they had solved the problem merely by shaping and arranging the razor parts so that when a flexible or cylindrically curved blade was clamped to position or flexed to cylindricity on the holder, the cutting edge of the blade would be obliquely inclined to the general line of extension of the handle on viewing the razor side-elevationally rather than in top plan. Other previous workers in the art have even gone so far, while cylindrically flexing their blades or even holding them flat, to propose that such blades have cutting edges which are regularly or irregularly curvilinear. Various other expedients have been resorted to heretofore, including the proposal that the blade, if a double-edge one, be made in the shape of a truncated triangle so as to permit the blade holder to be tapered toward one end thereof for the purpose of giving greater visibility and thereby avoiding the danger of cutting projecting parts of the ear or jaw, and that this blade be clamped in the holder and against a conical surface to have the blade transversely curved yet with its cutting edges perpendicular to the general line of extension of the handle on viewing the razor side-elevationally rather than in top plan.

What has been done by the present invention is to bring together, for the first time in simultaneous and cooperant action, in a hoe-type safety razor the blade of which has a straight cutting edge, two of the features each separately heretofore proposed by different workers in the art, but fallaciously so proposed, as itself the true answer to the problem of providing an automatic true slicing of said cutting edge; thereby actually and for the first time to solve that problem. In other words, the present invention is based on my discovery that the problem stated can be solved, and only solved, by providing in 40 one and the same hoe-type razor:

(a) A transversely curved or curvable blade having a straight cutting edge (such blade having, if desired, two cutting edges, one on each of the two opposite sides thereof);

(b) A holder for mounting the blade thereon in such manner as to curve or hold the blade curved in agreement with a conically curved surface the taper of which runs with the direction of extension of a cutting edge of the blade; 50 and

(c) A thus combined holder and blade so constituted that, with the razor viewed side elevationally rather than in plan, the general line of extension of the handle is perpendicular to the 55

general line of extension of the holder, and the blade's cutting edge is at an oblique angle both to the general line of extension of the holder and to the general line of extension of the handle.

5 A now preferred way of carrying out the invention, in a hoe-type razor, is to have the blade of substantially truncated triangular outline with cutting edges along both the inclined and converging sides thereof, to have said blade of the 10 thin flexible or ribbon type the origination of which is commonly ascribed to Gillette, and to have the blade clamping parts of the holder comprise mainly or wholly a blade table the upper surface of which is conically convex and a 15 blade cap the under surface of which is conically concave and the upper surface of which is conically convex. With such a razor, when the blade is clamped in the holder between the under surface of the cap and the upper surface 20 of the table, the oblique angularity of a cutting edge of the blade to the general line of extension of the handle automatically cooperates with the conicity of the blade and holder, when the razor handle is in the usual manner drawn over 25 the face, to cause the cutting edge of the blade so to move over the beard as to slip both longitudinally and laterally of the cutting edge to give a true slicing.

In the preferred form of the invention, further, and in order to provide a razor simple and inexpensive to manufacture, and easy to assemble and disassemble as well as easy to clean and dry in either condition, the handle is readily detachable from the holder, and the holder is 35 readily separable into table and cap.

Aside from satisfying the objects hereinabove indicated, the invention has as another object to provide means for insuring quick, proper and safe flexing of a flexible renewable blade, incidental to the insertion and clamping of the latter between the table and cap of the holder; such means taking the form of one or more elongate slots in the blade, preferably also substantially of truncated triangular outline, running lengthwise of the blade, and having the general line of extension and the opposite converging sides thereof if tapered projectable to meet at a common point with projections of the two converging cutting edges of the blade at 50 opposite sides thereof,—in combination with a protuberance or protuberances on the holder for accommodation within such slot or slots.

The invention will be more clearly understood from the following description, when taken in connection with the accompanying drawing. This drawing shows an embodiment of the invention as at present preferred; it being understood, however, that the showing thereof is merely illustrative of present preferences, and is not to be taken in any way in delimitation of the invention beyond the prescriptions of the appended claims, which claims of course define the scope of protection contemplated.

In said drawing,

65 Figure I is a side elevation showing the parts assembled.

Figure II is a perspective view looking toward the right in Figure I.

70 Figure III is a top plan view of the blade table of the holder.

Figure IV is a transverse section taken on the line 0—0 of Figure I.

75 Figure V is a bottom plan view of the blade cap of the holder.

Figure VI is a top plan view of one form of razor blade.

Figure VII is a similar view showing another form of blade.

Figure VIII is illustrative of the action of 5 razor and blade during shaving.

Referring first to Figures I to VI, both inclusive, there is shown a hoe-type safety razor including a handle 1, and a blade-holder comprising a blade table 2 and a blade cap 3; said holder for clamping and positioning a double-edge blade 4 to bring its opposite cutting edges 4e and 4d properly over marginal combs 2e and 2f of the blade table so that said table serves also as a safety or guard plate. The blade 4, substantially of truncated triangular outline, is provided with three slots 4a, 4b, and 4c therethrough; each of such slots also being substantially of truncated triangular outline, with the general lines of extension of the slots and their tapering sides converging in such manner relative to the convergence of the blade's cutting edges 4E and 4F that said edges, said general lines of extension, said sides, and the center line or axis A—A of the plate are all projectable 25 to meet at a common point 4G.

As best seen from a comparison of Figures I and II, the blade table 2 is conically convex on its upper surface except where interrupted by three protuberances 2b, 2c, and 2d, these protuberances similar in shape to and for entering respectively the blade slots 4a, 4b, and 4c; and the blade cap 3 has its under surface conically concave (except where interrupted by an upwardly extending recess 2b for receiving the tops of said protuberances where the latter extend through said blade slots to project above the blade 4) in correspondence to the conical convexity of the upper surface of the blade table 3. The upper surface of the blade cap 3 is smoothly conically convex all over, the cap being generally of crescent-form cross-section thereby laterally to thin down to opposite side edges 3c and 3d for overlying the side marginal portions of the blade 4 a slight distance in rear of the cutting edges 4e and 4d of said blade.

The slots in the blade, and the protuberances on the blade table, as shown, are circularly rounded at their opposite ends, these roundings merging smoothly with the tapering straight 50 sides of the slots and protuberances.

The protuberances fit nicely within the slots so as to set the blade's two cutting edges precisely as devised; and, by virtue of said slots and protuberances, a very thin blade can, without danger of cracking or otherwise being injured, be conically curved to an average radius of curvature laterally thereof much smaller than would otherwise be safe to attempt with an ordinary blade of the same shape and of the same thinness 60 and temper.

When the holder parts 2 and 3 are clamped tightly together, the former under the plate and the latter over the same, the blade is conically curved from end to end thereof, and safely to an average relatively small lateral radius of curvature as aforesaid; and, due to the bearing down of the side marginal portions of the blade cap 3 on the side marginal portions of the blade where the latter rest on the properly shaped upper sides of the teeth of combs 2e and 2f, these marginal portions of the blade can be given exactly the shaving set intended.

Then, it will be noted (comparing Figures I, II, and VI), the razor as a whole is substantially 75

T-shaped side elevationally, that is, as viewed in Figure I; and the general line of extension $1a$ of the elongate dependent handle 1 , constituting the staff of the T, is perpendicular to the center-line or axis A—A of the blade, which is also the axis of the conically convexo-concave blade cap, and substantially perpendicular to the general line of extension of the blade holder, constituting the bar of the T. At the same time, both cutting edges $4d$ and $4e$ of the blade, and also both guard combs $2e$ and $2f$, extend at an oblique angle to both the axis A—A and the general direction of extension of the handle, while the blade, and also the blade cap and said combs, are conically curved.

The means shown for assembling and disassembling the parts of the holder (here shown as comprising two parts, the blade table 2 and the blade cap 3), the blade 4 , and the handle 1 , include, as shown, the following elements: The upper end of the handle is axially bored and tapped to provide a socket having a cylindrical internal thread $1b$. This socket is for the reception of a stud $3a$, projected from the lower side of blade cap 3 and having an external thread matching the thread $1b$; the central slot $4b$ in the blade having a circular enlargement, and the blade table 2 having a circular hole, through which said stud is passed. In assembling or disassembling the razor, the handle is merely twirled in one direction or the other to screw the same on the stud up tightly against the underside of the blade table 2 or to screw the same loose from the blade table and off the stud.

The blade 4 as shown is arcuately curved at its opposite ends; but whatever be the shapings of these blade ends, preferably the distances between the ends of the slots in the blade, longitudinally of the general lines of extension of the slots, and said blade ends, are equal. The flexure of the blade, which as aforesaid is permitted to be markedly increased by the blade slots and their coacting protuberances within the holder, is around a single axis A—A. The blade when thus flexed is flexed to match a portion of the rotundity of a cone. Referring in this connection to Figure II, the degree of such flexure of the blade is a function of the radii of the arcs $2g$ and $2h$ of the blade table and of the arcs $3c$ and $3f$ of the blade cap; it being noted that, in accordance with present preferences, the upper sides of the combs $2e$ and $2f$ are shown as smoothly curved continuations of the arcuate lateral curvatures of the blade table at its upper side. The proper relative variation of said radii and/or of the curvatures of the upper sides of the comb teeth will give maximum efficiency of cutting action at each side of the razor.

During shaving, there is, when the razor is moved in the usual way over the face by ordinary pull on the razor handle lengthwise thereof, an automatic tendency of the holder and blade cutting edge applied to the face to have motions in two directions both at an angle to the direction of said pull. Referring to Figure VIII, there is an automatic tendency of the holder and the entire razor to move laterally of said pull and at a considerable if not a right angle thereto,—that is, in the direction of the line L—L, and in the direction of diminution of radius of curvature of the blade; and, simultaneously, an automatic tendency of the face-contacting cutting edge of the blade and contiguous comb $2e$ or $2f$ to move obliquely relative to the direction of pull, in fact almost per-

pendicular to the direction of extension of said cutting edge of the blade, as indicated by the line D—D. The resultant effect of these two tendencies toward movements in the directions of the lines L—L and D—D, simultaneously exhibited, is a movement of the holder and cutting edge in the direction of the line D—R; giving a true slicing of the hairs of the beard. This automatic movement of the holder and cutting edge in the direction of the line D—R is not only caused in part by the oblique inclination of the cutting edge to the general line of extension of the handle and consequently to the direction of natural pull lengthwise of said handle, and in part by the conical curvatures of blade and holder, but also (as the result of the conicity just referred to) by the fact that the axis A—A, although perpendicular to the general line of the handle, is obliquely inclined to the surface of the face being shaved. In other words, with the blade and holder-top curved conically pursuant to the invention, the cutting edge of the blade is not only obliquely inclined to the general line of extension of the handle side elevationally of the razor, but said edge is also obliquely inclined to the plane containing the axis of the cone and hence obliquely inclined to the axis A—A when the razor is viewed in top plan; and since in shaving the cutting edge is laid flat against the face, and the face is in the plane of said cutting edge, and the latter is obliquely inclined to the axis A—A when the razor is viewed in plan as just stated, said axis A—A is also obliquely inclined to the face.

Referring finally to Figure VII, the modified form of razor blade shown, also, desirably, a double edge one, differs from the blade illustrated in Figure V by the fact that, instead of a plurality of elongate and longitudinally tapering slots being provided in the blade, there is but a single such slot provided in the blade, and one so tapering longitudinally that while the center line thereof is projectable to meet at a common point projections of the cutting edges on opposite sides of the blade the tapering sides of said slot are substantially parallel to such cutting edges. This blade is also shown as having smoothly curvilinearly notched corners, as these in practice have been found to increase ease and safety in flexing the blade to lateral curvatures of comparatively small radius.

Wherever the blade or holder has been herein referred to as presenting a substantially truncated triangular outline, there is meant, preferably, as shown, the outline of an isosceles triangle truncated perpendicular to its altitude or parallel to its base.

What I claim as my invention and desire to secure by Letters Patent is:

1. A safety razor comprising a head and a handle, said head including cap and guard members and an interposed thin, flexible blade, said head being oblong but narrower at one end than at the other, means on said cap co-operating with said handle to draw the parts of the razor head together, said cap and guard members having minor portions comprising central zones defining a pronounced transverse curvature, said blade having a central slot and a slot on opposite sides thereof whereby the major portion of said blade is formed into sections united at their ends by flexible hinges, said cap and guard members having beyond said minor portions extensive guiding surfaces whereby the outer sections of said blade are clamped into positions which define planes which

if convergently extended would meet in a line at right angles to the axis of the handle, the edges of said blade defining a plane at a substantial inclination to the axis of said handle, whereby while shaving the drawcut action may be automatically produced in addition to the maintenance of a proper shaving angle resulting from the extensive guiding surfaces.

2. A safety razor comprising a head and a handle, said head including cap and guard members having an interposed thin, flexible blade, said members having a minor central zone portion of pronounced curvature, said head being oblong but narrower at one end than the other, means on said cap co-operating with said handle to draw the parts of said head together, said blade having a central slot and two similar slots on opposite sides of said central slot, thereby dividing the major portion of said blade into sections united at their ends by flexible hinges, said guard member having positioning means received by said slots, the major portion of said slots being defined by straight lines converging toward the narrow end of the razor, both sides of said razor head beyond said central zone forming extensive guiding surfaces which terminate in shaving edges substantially inclined to the axis of the handle whereby simultaneously both a proper shaving angle may be maintained and a drawcut action may be automatically produced substantially as described.

3. A razor, having a head including cap and guard members and an interposed thin, flexible blade, said head being oblong and narrower at one end than at the other, a handle for said razor, means on said cap and co-operating with said handle for drawing the parts of said razor head together, said blade having slots and said guard having positioning means received by said slots, the lines defining the major portions of said slots being straight and convergent toward the narrow end of the head, said razor head having a central zone defining a pronounced curvature having its axis at substantially right angles to the axis of the handle, the remaining portions of said head defining smooth, extensive guiding surfaces which terminate in shaving portions inclined substantially to the axis of the handle whereby the razor may be guided at a proper shaving angle across the face and produce in addition automatically the drawcut action of an inclined edge, substantially as described.

4. A safety razor head having cap and guard members and an interposed thin, flexible blade, said members and blade being oblong and narrower at one end than at the other, a handle for said razor means on said cap in co-operation with said handle for drawing the parts of said razor head together, the long edges of said cap, blade and guard being obliquely inclined to the axis of the handle and adapted to produce automatically a drawcut action when said razor is drawn across the face in shaving, the outer portions of said blade being supported in planes by said members, the outer major portions of said head defining extensive guiding surfaces to facilitate guiding the razor over the face at a proper shaving angle in addition to maintaining the automatic drawcut action.

5. A razor blade having straight shaving edge portions on each of its opposite side edges, said

blade having one broad end and its opposite end comparatively narrow whereby said shaving edges define lines inclined oppositely relative to the longitudinal central axis of said blade, the major portion of said blade being divided longitudinally into sections by a plurality of longitudinal slots, one of said slots being centrally arranged, with at least one of the other slots located between the central slot and each cutting edge, the edges of said sections and slots being defined at least throughout the major portion thereof by straight lines, said lines converging toward the narrow end of the blade whereby said lines, if sufficiently projected beyond said narrow end, will all meet in a point, said slots adapted to receive positioning means.

6. A safety razor comprising a head and a handle, said head including cap and guard members and an interposed thin, flexible blade, said head having one end narrower than the other, said blade having a plurality of slots extending longitudinally thereof, one of said members having blade positioning means received by said slots to properly align the blade and members, said members having minor portions of pronounced curvature comprising central zones, the remaining portions of said members being of reduced or slight curvature and terminating in edges defining planes at an oblique angle to the handle, said portions supporting the outer shaving edge portions in planes at a proper pitch to the handle as well as the inclined blade edges in a drawcut position, said cap member defining plain smooth extensive guiding surfaces whereby the razor may be guided at an efficient pitch over the face in shaving for simultaneously and automatically producing in co-operation with said inclined razor edge an effective drawcut action substantially as described.

7. A safety razor having a handle, cap and guard members and a wafer-type blade interposed between said cap and guard members, said members and blade being oblong and narrower at one end than at the other, means for drawing the cap and guard members together to cause them to clamp the blade between them, the long edges of the cap, blade and guard being obliquely inclined to the axis of the handle and adapted to produce automatically a draw-cut action when said razor is drawn across the face in shaving, the blade when clamped in cutting position lying wholly in a curved surface having a straight line generatrix and having its cutting edges lying in a straight line which is inclined both to a plane perpendicular to the handle and to a plane defined by the center line of the handle and a straight line lying in the curved surface and intersecting said center line.

8. A safety razor having a thin flexible blade wider at one of its ends than at the other, a handle, clamping means between which the blade is flexed, said clamping means being so shaped that they flex the blade and hold it in cutting position so that it lies in a curved surface corresponding to a portion of the surface of a cone, with the cutting edge of the blade coinciding with the generatrix of said surface and lying obliquely with respect to a plane perpendicular to the handle.
